UNITED STATES PATENT OFFICE.

HERMAN SILVER, OF MINNEAPOLIS, MINNESOTA.

CUPOLA-VENTILATOR FOR BARNs AND THE LIKE.

1,312,586.

Specification of Letters Patent. Patented Aug. 12, 1919.

Application filed November 15, 1918. Serial No. 262,650.

To all whom it may concern:

Be it known that I, HERMAN SILVER, a citizen of the United States, residing at Minneapolis, in the county of Hennepin and 5 State of Minnesota, have invented certain new and useful Improvements in Cupola-Ventilators for Barns and the like; and I do hereby declare the following to be a full, 10 clear, and exact description of the invention, such as will enable others skilled in the art to which it appertains to make and use the same.

My invention has for its object to provide an extremely simple and highly efficient ventilating cupola for barns and the like; and, to this end, it consists of the novel devices and combinations of devices herein-after described and defined in the claim.

In the accompanying drawings, which 20 illustrate the invention, like characters indicate like parts throughout the several views.

Referring to the drawings,

Figure 1 is a view of the improved ventilating cupola partly in elevation and partly in central vertical section;

Fig. 2 is a horizontal section taken on the line 2—2 of Fig. 1;

Fig. 3 is a view partly in plan and partly 30 in horizontal section taken on the line 3—3 of Fig. 1;

Fig. 4 is a fragmentary detail view showing one of the brackets from which the inner band is directly supported from the 35 flue and from which brackets the cap is indirectly supported; and

Fig. 5 is a detail view partly in elevation and partly in vertical section taken on the line 5—5 of Fig. 4.

40 The entire cupola is preferably constructed from heavy galvanized metal and comprises a rectangular base 6, flue 7, cap 8, and inner and outer concentric bands 9 and 10, respectively. The base 6 has, at its upper end, 45 a wooden reinforcing frame 11 to give the same the necessary rigidity and which base may be cut to fit roofs of different pitch. The flue 7 is made in upper and lower sections, the latter of which is square at its 50 lower end and caps a flange 12 on the base 6 to afford a rain-proof joint therebetween. The upper end of the lower flue section is round and is rigidly secured to the lower end of the cylindrical upper section of said 55 flue by a weather-tight joint 13.

Circumferentially spaced radial brackets

14 rigidly connect the inner band 9 to the flue 7. The vertex of the band 9 is turned toward the flue 7 and spaced apart therefrom to afford an air passageway therebetween. As shown, the brackets 14 are in the form of flat plates set vertically edge-wise and have their ends bent laterally to afford inner flanges 16 and outer flanges 17. The inner flanges 16 bear directly against 65 the outer face of the flue 7 and are secured thereto by rivets 18. The outer ends of the brackets 14 are notched to receive the V-shaped inner band 9, and the outer flanges 70 17 follow the contours of the outer ends of the inner band 9, directly to engage said band, and are detachably secured thereto by bolts 19. By reference to Fig. 1, it will be noted that the upper edges of the flue 7 and the inner band 9 are in substantially 75 the same horizontal plane.

The cap 8 is vertically spaced above the flue 7 to afford a horizontal air passageway therebetween, and is supported from said flue by a plurality of circumferentially 80 spaced braces 20, in the form of horizontally disposed U-shaped members. The prongs of the braces 20 extend inward and their free end portions are bent into diverging relation, so that the lower prongs bear directly 85 upon the upper portions of the flanges 17, and are detachably secured thereto by the respective bolts 19, and the upper prongs of said braces extend within the cap 8 and are detachably secured thereto by bolts 21. 90 The outer band 10 is detachably secured to the transverse portions of the braces 20 by bolts 22 and the diameter thereof is considerably greater than the diameter of the inner band 9, so as to afford a vertical air 95 passageway that intersects the horizontal air passageway between the flue and cap. By reference to Fig. 1, it will be noted that the band 10 extends below the upper horizontal edge of the band 9 and above the lower 100 horizontal edge of the cap 8.

The cap 8 is of conical shape and it will be noted that the same projects considerably outward of the flue to prevent rain and snow from entering the same. Within the 105 cap 8, is secured an inverted relatively flat conically formed bottom or deflecting plate 23. An annular screen 24 extends between the flue 7 and cap 8 to prevent birds, bats, etc., from entering the cupola. Downward 110 air currents will pass between the cap 8 and outer band 10 intersecting the horizontal air

passageway between the flue and cap and also through the two vertical air passageways formed by the two bands 9 and 10, as indicated by arrows at the left in Fig. 1. 5 Upward currents of air will move in reverse directions from those just described and, as indicated by arrows at the left in Fig. 1. The cap bottom 23 will deflect the 10 ventilating draft, through the cupola, outward, in all directions, and prevent the forming of an air pocket in the cap. Foul air in the building will pass upward 15 through the base 6 and flue 7 and strike the conical bottom 23 of the cap 8 and be deflected thereby in all directions outwardly and upwardly between the cap 8 and band 10. Upward air currents striking the outer surface of the flue 7 will pass upward 20 through the air passageway 15 and between the cap 8 and band 10, commingling with the foul air from the flue, and thereby cause a forced draft in said flue. Obviously the upper and outwardly diverging portion of the band 9 will deflect up-

ward outside air currents, striking the same, 25 into substantially parallel movement with the foul air discharging from the flue, and thus prevent the same from entering the flue.

What I claim is:—

30 A ventilating cupola having a flue, a cap and inner and outer bands, said inner band being V-shaped in cross section with its vertex spaced apart from the flue to afford an air passageway therebetween and with 35 its flanges diverging from said flue, radial brackets secured to the flue and having in their outer ends V-shaped notches to receive the inner band which is secured thereto, and brackets supporting the outer band 40 from the cap and inner band.

In testimony whereof I affix my signature in presence of two witnesses.

HERMAN SILVER.

Witnesses:

CLARA DEMAREST,
HARRY D. KILGORE.
